UNITED STATES PATENT OFFICE.

JAMES FRANK STOCKING, OF EAST ORANGE, NEW JERSEY.

DESIGN FOR A FILTER.

47,970.

Specification for Design.

Patented Oct. 12, 1915.

Application filed March 2, 1915. Serial No. 11,570. Term of patent 14 years.

To all whom it may concern:

Be it known that I, JAMES FRANK STOCKING, a citizen of the United States, residing at East Orange, in the county of Essex and State of New Jersey, have invented a new, original, and ornamental Design for Filters, of which the following is a specification, reference being had to the accompanying drawing, forming a part thereof, and in which—

Figure 1 is an elevation of a filter showing my new design, and Fig. 2 is a plan view of the filter looking from the top.

The filter comprises a hollow body portion of substantially cylindrical configuration having reduced ends and provided with a plurality of ornamental vertical ribs

spaced at intervals around the periphery of the body, which give the filter a massive, strong and attractive appearance. Horizontal ribs, extending part way around the body, may be provided, as shown in the drawing, to form a frame surrounding a space, in which the trade-name or mark of the article may be inserted.

I claim as my invention and desire to secure by Letters Patent:

The ornamental design for a filter, as shown and described.

JAMES FRANK STOCKING.

Witnesses:
